UNITED STATES PATENT OFFICE

CHARLES R. KEERAN, OF EVANSTON, ILLINOIS

PENCIL

Application filed November 7, 1930. Serial No. 493,931.

The purpose of this invention is to provide an improved construction particularly adapted for use in mechanical pencils and relating to a means for securing the usual clip in its position in the barrel, such means being combined in the preferred form of the invention with a magazine for spare leads and a holder for a removable eraser. The invention consists of certain features and elements of construction as herein shown and described, and as indicated by the claims.

In the drawing:

Figure 1 is a side elevation of a mechanical pencil with the upper portion of the barrel, the clip and the clip-securing means shown in section to illustrate the features of this invention.

Figure 2 is a longitudinal sectional view of the upper portion of the pencil barrel with its clip-securing means of modified form.

Figure 3 is a transverse section taken as indicated at line 3—3 on Figure 1.

Figure 4 is a transverse section taken as indicated at line 4—4 on Figure 2.

Figure 5 is a partial longitudinal section similar to Figure 2 showing a further modification of the clip-securing means.

Figure 6 is a fragmentary sectional view showing the clip in the process of assembly and a retaining plug partially inserted in the barrel.

The lead-propelling mechanism which may be understood as housed in the lower or tipped end of the pencil barrel, 1, may be of any suitable type and has no particular relation to the present invention; therefore it is not illustrated in detail and need not be further described. The upper portion of the barrel, 1, is hollow, as is usual in pencils of this type, having a bore indicated at 2. For holding the pencil upright in a coat or vest pocket the barrel is equipped with a spring clip whose external portion is in the usual form of a tapering arm, 3, preferably terminating in a spherical formation at 4 and bent transversely at 5 to enter an opening in the form of a slot, 6, in the wall of the barrel, 1. Inside the barrel the clip member terminates in a tang, 7, bent approxi-

mately at right angles to the transverse portion, 5, so as to extend substantially parallel to the spring arm, 3, and to the axis of the barrel, 1, in its assembled position.

The tang, 7, of the clip member is held in place by a plug, 8, inserted in the upper end of the barrel and accurately fitting the bore, 2,—preferably so that the plug must be forced in under considerable pressure and is held tightly enough in the barrel to be considered a permanent fixture therein. In the form shown in Figure 1 the inner wall of the barrel is formed with a groove, 9, extending longitudinally from the slot, 6, to the open end of the barrel and dimensioned to accommodate the tang, 7, of the clip member, the depth of the slot being substantially equal to the thickness of the tang.

In the form shown in Figure 2 the inner wall of the barrel is unbroken except by the slot, 6, but a longitudinal groove 19 is provided in the outer wall of the plug, 18. In the second modification which is shown in Figure 5, the plug, 28, instead of being forced into the bore of the barrel, 1, is formed with a short thread, 29, near its upper end which engages corresponding threads formed on the inner wall of the barrel so that the plug, 28, may be screwed home to position for locking the tang, 7, in the groove, 9, of the barrel.

With any of the plug structures just described it will be evident that the assembly of the clip with the barrel becomes an extremely simple matter. It is only necessary to enter the tang, 7, in the slot of the barrel and then swing the tang bodily in the slot, thus rocking the curved part, 10, of the transverse portion, 5, into place and bringing the tang flatly against the inner wall of the barrel or the bottom of the longitudinal groove in that wall; then the insertion of the plug firmly locks the tang of the clip in this position. If the plug is not too tightly fitted, or is screwed into position, as shown in Figure 5, the breakage of the clip, 3, becomes a very simple matter to repair because it merely involves removal of the plug and insertion of a new tang. This can usually be done by the retail dealer and thus avoid

shipment of the pencil to the factory for this repair.

In order to utilize the space in the barrel efficiently I prefer to make the plug, 8, or 5 either of its modified forms, 18 or 29, hollow so as to serve as a chamber or reservoir for spare leads, which are indicated in this position at 11 in Figures 1, 3 and 4. And preferably I combine with the hollow plug as an 10 integral portion thereof a somewhat larger cylindrical head, 12, which is also hollow and serves as a socket for the usual rubber eraser, 13. The eraser is shown pocketed in a spring holder, 14, whose spring arms terminate 15 in gripping prongs, 14^a. Adjacent these prongs the arms are bent angularly outward to act as stop flanges, tending to limit the insertion of the spring holder into the socket, 12, and also serving as a convenient 20 projection to be engaged by the fingers in removing the eraser bodily from the socket, 12. When the spring holder is thus removed its prongs tend to open, thus releasing the eraser, 13 and permitting it to be 25 re-adjusted, usually outwardly, to compensate for wear; or the eraser may be completely removed and replaced by a new one, whereupon the spring holder will be re-inserted in the socket, 12. Occasionally, it may be difficult 30 to grasp the eraser unit at the bends, 14^b, and in such instances a pin or similar implement may be inserted in the aperture, 16, of the socket, 12, said aperture being located opposite the lower edge of the spring 35 holder, 14, as indicated in Figure 5.

It will be understood, of course, that any manipulation or adjustment of the eraser is carried on after removal of the outer ornamental cap, 20, if such cap is provided, although 40 in more inexpensive grades of pencils this cap may be entirely omitted from the structure. Such cap, 20, is merely held by frictional engagement with the outer surface of the socket, 12.

45 The hollow plug, 8, and its connected socket portion, 12, may be formed from sheet metal by well known methods similar to those used in the drawing of cartridge shells, the bottom wall of the hollow plug being left in place to 50 serve as the bottom of the spare lead chamber, thus avoiding the expense and work of inserting a special plug or diaphragm to perform this function. When the barrel, 1, is formed of bakelite, celluloid or other molded 55 composition it is a simple matter to hold the groove, 9, in forming the main bore, 2. But when the barrel is to be of metal tubing or any standard tubing it may be considered preferable to employ the form of plug shown 60 at 18 in Figure 2, in which the groove, 19, is pressed into the wall of the plug itself so that no special formation is required in the bore of the barrel, 1^a.

I claim:

65 1. In a writing implement including a hol-

low cylindrical body with an aperture in its wall, a clip comprising a portion extending through said aperture with a yieldable arm bent transversely of said portion and lying along the outside of the barrel, and a tang 70 also bent transversely of said portion but extending within the barrel in contact with the inner wall thereof, together with a plug inserted in the barrel and dimensioned to grip the tang between its outer wall and the inner 75 wall of the barrel, said plug having a hollow portion at its outer end extending beyond the barrel serving to hold an eraser, the barrel having a groove to accommodate the tank of the clip, and the plug and barrel having co-operating threaded portions by which the plug is retained in clip-holding position.

2. In the combination defined in claim 1, said plug being in the form of a hollow shell having a portion adapted to serve as a magazine 85 for spare writing points for the implement, the eraser being removably held in the outer end portion of the plug and serving as a closure for said magazine.

3. In a pencil, a hollow barrel having an 90 aperture in its wall, a clip comprising a portion extending through said aperture, a yieldable arm bent transversely of said portion and lying along the outside of the barrel, and a tang also bent transversely of said portion 95 extending within the barrel in contact with the inner wall thereof, together with a plug inserted in the barrel and firmly held therein against longitudinal movement to grip the tang between its outer wall and the inner wall 100 of the barrel, said plug being in the form of a hollow shell closed at the inner end having a portion adapted to serve as a spare lead magazine for the pencil, and a portion at its outer end of larger diameter serving to hold 105 an eraser and forming a shoulder at the junction of said portions to abut the end of the barrel for limiting the insertion of the smaller portion therein.
